UNITED STATES PATENT OFFICE.

JOHN REDER, OF NEW YORK, N. Y.

CUTLERY SHARPENER.

Application filed January 25, 1922. Serial No. 531,546.

To all whom it may concern:

Be it known that I, JOHN REDER, a citizen of the United States, residing at New York, in the county of New York and State of 5 New York, have invented certain new and useful Improvements in Cutlery Sharpeners, of which the following is a specification.

This invention relates to cutlery sharpening devices, the main object being to provide a device having a carborundum wheel mounted between frames and having slots which form guides for holding a shears blade or similar other tool, at the proper angle while being ground.

Another object is to provide a means for rotating the said carborundum wheel, after the latter has been worn, so as to present a new surface to the tool, thus utilizing the whole periphery of the said wheel.

These and other objects will become apparent in the description below, in which like characters of reference refer to like-named parts in the drawing.

Referring briefly to the drawing, Fig. 1 is a front elevational view of the device mounted on a table.

Figure 2 is a side elevational view of the same.

Figure 3 is a front elevational view of a modified form of device having means for rotating the carborundum wheel.

Figure 4 is a side elevational view of the same.

Figure 5 is a perspective view of the screw shifter block used in the modified form of device.

Describing the drawing more in detail, numeral 1 indicates a table or bench. Altho the device is shown mounted on a table, 40 it may also be mounted on a wall or any other position desired.

The device consists substantially of a frame base 2 to which a pair of plate members 3 are permanently secured.

These plates 3 have upwardly extending ears 4 which form side frames for an annular carborundum wheel 5. A screw 6 threadably engages one of the side frames and forms a shaft about which the wheel 5 is 50 rotated. The side frames begin to curve outwardly, as indicated by numeral 7 after passing center screw 6 forming relatively long tapering slits 8 and are adapted to re-

ceive a knife blade or the like securely against the surface of the wheel 5. The side frames are further provided with slotted runways 9 and 9' located in such manner as to present the tool to the wheel at the proper angle to form the necessary clearance angle to the cutting edge. The slot 9 is particularly adaptable for shears while 9' is for chisels or the like.

Figures 3 and 4 illustrate a modified form of device identical to the preferred form but has in addition an inclined extension 10 integrally formed to both side frames 4. A rectangular recess 11 in said extension receives a shifter block 12 and is slidably retained by the guide lugs 18 which engage corresponding guide slots formed in the said extension 10.

A threaded stud 13 is pivoted in a socket lug 14 at the lower end shoulders on block 12 and has a stem 15 which passes thru hole 16 of block 12 and extends somewhat 75 above the surface. A feed screw 17 located in extension 10 engages the end of shifter block 12 and when rotated in the required direction will urge the said block toward wheel 5.

In use, a knife blade is inserted into one of the slits 8 and run thru its length, back and forth, until the desired edge has been obtained. In sharpening shears or other tools, the operation is the same, but runways 85 in the side frames are used to give the same the proper clearance angle. Obviously, continued use of the device will form nicks and indents in the wheel. In the preferred form loosening the screw 6 will permit the wheel to 90 be rotated, manually, to a new surface. In the modified form, a screw driver or like tool is inserted in slot of extension 15 and rotated. Threaded stud 13 contacting with the periphery of wheel 5 will slowly rotate 95 the said latter, thus permitting the slight angular adjustment to a new and unused surface.

When changing the wheel for one of smaller or larger diameter, screw 17, when 100 manipulated, will permit radial adjustment of stud 13 to give proper feed contact with the new size of wheel.

I claim:

A cutlery sharpener as described comprising a pair of angular side frames fixed to

a frame base and having inclined slotted runways, a carborundum wheel between said side frames, an extension integral with the side frames, a shifter block slidably mounted in said extension, a threaded stud rotatable in said block and contacting with the periphery of the carborundum wheel, a slotted stud adapted to rotate said threaded stem,

a screw adapted to urge the shifter block toward the wheel and means for rotating said carborundum wheel by rotating the threaded stem when both elements are in mutual contact.

In witness whereof I, affix my signature.

JOHN REDER.
